GAS RANGE

Arnold L. Rose, Larchmont, N. Y.

Application October 28, 1941, Serial No. 416,784

5 Claims. (Cl. 126—39)

This invention relates to improvements in gas ranges and has for a main object the improvement of the external appearances of ranges, the reduction in weight thereof, and simpler and more effective methods of insulating gas ranges.

Another object of the invention is the provision in gas ranges of improved wall construction, including panels formed of composite pressed boards which are fireproof, have admirable insulating qualities, and the outer surfaces of which are capable of taking a fine finish.

A further object of the invention is the provision in gas ranges of composite panels which not only provide insulation, but also carry the desired finishes on the outer surfaces thereof.

A further object of the invention is the provision in a gas range of the "sky-scraper" type, of a recessed or stepped-in break in the front of said range at the base thereof, permitting the user to stand closer to the range when desired.

Other objects of the invention will be apparent to those skilled in the art.

Referring now to the drawing—

Figure 1 is an external perspective view of a range made according to the invention;

Figure 2 is a sectional elevation of the range shown in Figure 1 showing structural details thereof;

Figure 3 is a sectional view taken along the line 3—3 of Figure 2;

Figure 4 is an enlarged sectional view of a portion of the device shown in Figure 2; and

Figure 5 is a fragmentary view in section showing a wall structure of the prior art.

The range, generally designated by the numeral 10, is tall and is generally of rectangular cross section. At the top of the range is the burner section 11, which is provided with a removable cover 12. This cover may either be hinged to the range at the back near the splash-plate 13, or it may be removable. The burners 14 are controlled by valves 15 and are positioned in the burner compartment 16. Beneath the burner compartment is an oven 17 which is separated from the burner compartment by an insulated wall 18.

In the side walls of the oven are aligned projections 19 upon which suitable shelves 20 may be positioned. Beneath the oven is a broiler compartment 21 which is separated from the oven proper by the plate 22. Below the plate 22 is a burner 23 which supplies heat for both the broiler and the oven.

The burner 23 is controlled by an automatic valve 24. The projections 25 in the side walls

of the broiler chamber are provided for supporting a pan 26. The projections 25 are spaced apart from each other, thereby permitting the pan 26 to be positioned within the broiler.

5 A door 27 is hingedly mounted on the range for giving access to the oven, and this door is provided with a suitable handle 28. A second door 29 is hingedly mounted on the range for access to the broiler, and this door is likewise provided with a handle 30.

The left side 31 of the range has its lower front corner cut away to form a recess 32 therein. The right side 33 of the range has its front corner cut away to form a recess 34 therein. These recesses are in alignment with each other and are covered by a kick-plate 35 which is substantially parallel with the front of the range but spaced apart rearwardly therefrom. This permits the user of the range to step up closer to the front of the range, which is advantageous particularly when using the rear burners.

Figure 3 is a sectional view taken along the line 3—3 of Figure 2, and shows the angle iron frame and the method of securing the walls thereto. The side and back walls, and also the doors, are provided with insulations.

Referring now to Figure 4, which is an enlarged fragmentary sectional elevation, showing details of construction. For example, the bottom of the burner compartment 16 is provided with a sheet metal lining 36, and the upper surface of the oven compartment is also bounded with a sheet metal lining 37. Between the linings 36 and 37, suitable insulation 38 is provided.

35 Within the compartment 16, the lining 36^a extends upwardly, and within the oven compartment the lining 37^a extends downwardly, and carries the aligned projections 19. The lining 37^a extends downwardly in the broiler compartment and has formed integral therewith the projections 25.

40 The outer wall 40 is preferably formed of asbestos or other heat resistant material or compound which have been compressed and the outer surface of which is very hard. Suitable insulation 39 is provided in the space between the outer wall 40 and the linings 36^a and 37^a.

45 The insulations 38 and 39 may be formed of loose insulating material which is packed in, or it may be formed of pressed material and put in in sheets. Another arrangement contemplates the use of a composite material the outer surface of which is provided with a hard finish and the remainder of which is less hard and particularly adapted for insulating purposes.

In the latter instance the labor of constructing the ranges is materially reduced because in applying the sheets of material, the proportion thereof adapted as an insulator is automatically positioned in place when the sheet is applied, and the outer wall with its hard surface is particularly adapted for receiving the finish. In some instances it has been found advantageous to apply the finish to the hard surfaces of the sheets before the sheets are assembled into the range. I have found that almost any type of finish may be applied to the outer surfaces of these sheets in as many coats as desired, and when a particularly fine finish is desired the preceding coat may be rubbed so as to enhance the final finish.

In Figure 5 is shown a fragmentary view illustrating the method of finishing ranges of the prior art, wherein packing or insulation 43 is positioned between the inner middle wall 44 and the outer middle wall 45 on the sides, and between the upper middle wall 46, a break strip 47 being provided between the inwardly turned edges of the top wall 46 and the side 45.

The herein described method has distinct advantages over this type of construction in that the thin sheets of metal 45 and 46, after being finished with a vitreous enamel are subject quite often to having the enamel flake off in places while the material is being handled, and quite often the flaking-off occurs in the most conspicuous place. With my new type of construction herein shown and described, finishes equal to the vitreous finish can be obtained and there is no chance for this finish to flake off.

Another important advantage with my new form of construction is that the weight of the finished range is substantially reduced, thereby making it more easily handled.

Further, it must be understood that my new form of construction, although described in connection with a "skyscraper" type of range, this type of construction is equally applicable to tabletop forms of ranges, and in cases where the exterior walls of the range extend to the floor, the break-front type of construction may be applied to the fronts thereof.

It must also be understood that although the example herein given is described as using gas for fuel, the types of construction shown and claimed are equally applicable to ranges in which the source of heat is any other medium, such as electricity, oil, coal, coke, wood, or high frequency oscillations.

Although I have herein described by way of example a gas range embodying the invention, it is obvious that many changes may be made from the arrangement herein shown and described without departing from the spirit of the invention as set forth in the annexed claims.

What is claimed is:

1. A gas range having exterior walls formed of composite fire-proof pressed boards, an oven in said range interiorly bounded by thin metallic walls and insulation material between said metallic walls, and said non-metallic walls, said exterior walls augmenting the insulating effect of said material and having at least their external surfaces substantially hard and carrying a high finish.

2. In a gas range, a flat top burner compartment, an oven below said compartment and having its interior defined by thin metallic walls, a thin metallic wall between said burner compartment and said oven, insulating material between said last wall and the top wall of said oven, exterior walls on said range spaced apart from the side walls of said oven, at least one of said walls carrying a door permitting access to said oven, and insulating material between said exterior walls and the side walls of said oven, said exterior walls being comprised of composite pressed boards of fire-proof insulating material, the external surfaces at least of which have been hardened whereby a high finish may be applied thereto, the insulating effect of said composite boards serving to augment the insulating effect of said insulating material.

3. In a gas range, a flat top burner compartment, an oven below said compartment and interiorly bounded by thin metallic walls, a thin metallic wall between said burner compartment and said oven, insulating material between said last wall and the top wall of said oven, and exterior walls in said range spaced apart from the side walls of said oven and at least one of them carrying a door permitting access to said oven, said exterior walls being comprised of fire-proof composite pressed boards forming an additional insulator and having an exterior surface sufficiently hard to carry a highly glossy finish of enamel or the like.

4. A range having exterior walls formed of composite fire-proof boards and including an oven, thin metallic walls bounding the interior of said oven, an insulation material between said metallic walls and said non-metallic walls, said boards constituting additional insulation and being comprised of a heat resistant compound in which the density and hardness of the material is greatest on the exterior surface thereof.

5. The invention according to claim 3, in which the density or hardness of the pressed boards forming said exterior walls is greatest on the exterior surfaces of said boards.

ARNOLD L. ROSE.
